BOTTLE

Lyle F. Sampson, Piedmont, Calif., assignor to Owens-Illinois Glass Company, Toledo, Ohio, a corporation of Ohio

Application August 22, 1957, Serial No. 47,474

Term of patent 14 years

(Cl. D58—8)

Fig. 1.

Fig. 2.

Fig. 3.

Fig. 4.

Fig. 1 is a side elevational view of a bottle, showing my new design.

Fig. 2 is a side elevational view with the bottle rotated 90° from the position in Fig. 1.

Fig. 3 is a bottom plan view.

Fig. 4 is a fragmentary sectional view taken substantially at the line 4—4 of Fig. 1 on an enlarged scale.

The sides not shown are the same as the sides shown.

I claim:

The ornamental design for a bottle, substantially as shown and described.
